RAILWAY TRAFFIC CONTROLLING APPARATUS

Paul P. Stoker, Wilkinsburg, Pa., assignor to The Union Switch & Signal Company, Swissvale, Pa., a corporation of Pennsylvania

Application February 3, 1928, Serial No. 251,576
Renewed April 30, 1930

32 Claims. (Cl. 246—3)

My invention relates to railway traffic controlling apparatus, and particularly to apparatus of the type intended for safely controlling railway traffic governing devices, such as railway switches and signals from a remote point.

I will describe one form of railway traffic controlling apparatus embodying my invention, and will then point out the novel features thereof in claims.

10 The accompanying drawing is a diagrammatic view showing one form of railway traffic controlling apparatus embodying my invention.

Referring to this drawing, the reference characters 1 and 1^a designate the track rails of a 15 stretch of railway track connected with a siding 4, by a switch 3 of the usual and well known form. The rails 1 and 1^a of the main track are divided, by means of insulated joints 2, to form a plurality of successive track sections A—B, B—C, C—D, 20 D—E, and E—F. The rails of siding 4 are also divided by means of insulated joints 2 to form a track section G—H, the rails of the siding to the left of point G being connected with the rails of section C—D in accordance with the usual practice. 25 Each track section is provided with a track battery 10 connected across the rails adjacent one end of the section, and with a track relay connected across the rails adjacent the other end of the section and designated by the reference character R with a suitable distinguishing exponent. Each track relay R is normally energized, but is arranged to open when a train 30 enters the corresponding section.

Associated with the switch 3 is a circuit controller designated in general by the reference character J. When the switch 3 is in its normal position, in which it is illustrated in the drawing, contacts 5—5^a and 6—6^a are closed. When the switch occupies its reverse position, contacts 5—5^b 40 and 6—6^b are closed. The circuit controller J also comprises contacts 8—8^a and 9—9^a which are closed at all times except when the switch occupies its reverse position. Contacts 8—8^b and 9—9^b are closed at all times except when the switch occupies its normal position. The reference character 7 designates a pole-changer by means of which a polar indication relay K is connected with the terminals X and Y of a suitable source of energy not shown in the drawing. With this arrangement, when switch 3 occupies its normal position, the relay K is energized in one direction so that the polar contact 50 is swung to the left. When switch 3 is reversed, however, the pole-changer 7 reverses the polarity

of the current supplied to relay K and causes polar armature 50 to swing to the right.

Westbound traffic, that is, traffic moving from right to left, over the portion of track shown in the drawing is controlled by two signals S² and S⁴, and traffic in the opposite direction is controlled by two similar signals S¹ and S³, which in the form here shown are mounted on the same mast. The signals S are illustrated in the drawing as semaphore signals, but this particular form is not essential. The switch 3 and the signals associated therewith are arranged to be controlled manually from a remote point. In the form of apparatus here illustrated, this is accomplished by means of a plurality of selectors, 65 each designated by the reference character W with a distinguishing exponent and each comprising an operating winding 11 and a contact controlled thereby. The operating windings 11 of all the selectors are connected in 70 parallel across a pair of line wires 97 and 97^a. The selectors W are selectively responsive to control codes which may be impressed upon the line wires 97 and 97^a by any suitable means. It is frequently desirable to control the selectors by 75 means of a code transmitter indicated diagrammatically at T and located at some central control point such for example as a train dispatcher's office. Each of the selectors W¹, W², W³ and W⁴ 80 comprises a normally open contact 12 which is arranged to be closed for a brief interval of time when the corresponding selector receives its proper control code. The selector W⁵ comprises 85 a normally closed contact 12^a which is arranged to be opened for a brief interval of time when selector W⁵ receives its proper control code. 90

The reference characters Q^E and Q^W designate two signal relays which, or traffic direction stick relays, are controlled by the selectors W³, W⁴ and W⁵. The relay Q^E is provided with a pick-up 95 circuit which may be traced from terminal X of a suitable source of energy not shown in the drawing through contact 12 of selector W³, wires 13 and 14 and winding of relay Q^E, to the terminal Y of the same source. Relay Q^E is also provided with a stick circuit from terminal X, over contact 12^a of selector W⁵, wires 15 and 16, back contact 17 of relay Q^W, wire 18, front contact 19 of relay Q^E, wires 20 and 14, and winding of relay Q^E, to terminal Y. It is plain, therefore, that relay Q^E 100 may be energized by operating selector W³ and that after the relay has once picked up, it will be maintained in its energized condition until relay Q^W is closed to open back contact 17, or until selector W⁵ is operated to open contact 12^a. 105

When relay Q^E is energized, signal S^1 or signal S^3 is cleared depending upon the position of switch 3. If the switch occupies its normal position, current flows from terminal X over wire 56, front contact 57 of track relay R^3 , wires 58, 59 and 60, front contact 61 of relay Q^E , wire 62, contact 6—6^b of circuit controller J, wire 63, and operating mechanism of signal S^1 to terminal Y. If switch 3 occupies its reverse position, the energization of relay Q^E completes an operating circuit for signal S^3 which may be traced from terminal X, over wire 56, front contact 57 of relay R^3 , wires 58, 59 and 60, front contact 61 of relay Q^E , wire 62, contact 6—6^b of circuit controller J, wire 64, and operating mechanism of signal S^3 to terminal Y. It follows therefore that if section C—D is unoccupied and if relay Q^E is energized, signal S^1 or signal S^3 will be cleared according as switch 3 occupies its normal or its reverse position.

In similar manner, the signals S^2 and S^4 governing westbound traffic are controlled by relay Q^W and this relay is provided with a pick-up circuit controlled by selector W^4 and a stick circuit controlled by relay Q^E and selector W^5 . The circuits for relay Q^W are similar to the circuits already traced for relay Q^E and will be readily understood from the drawing without further explanation.

The switch 3 is controlled in part by two approach locking relays L^1 and L^2 . Referring first to relay L^1 , this relay is provided with a pick-up circuit from terminal X, over wire 21, back contact 22 of track relay R^3 , wires 23, 24 and 25, and winding of relay L^1 to terminal Y. The relay L^1 may also be energized by actuating a manually operable push button Z which is preferably located in the trackway adjacent the switch 3. When this push button is operated, current flows from terminal X, through wire 26, contact 98 of push button Z, wires 27, 28, 24 and 25, winding of relay L^1 to terminal Y. Relay L^1 is also provided with a stick circuit from terminal X, over wire 29, back contact 30 of relay Q^E , wire 31, front contact 32 of relay L^1 , wires 33 and 25 and winding of relay L^1 to terminal Y. Still another stick circuit is provided for relay L^1 which may be traced from terminal X, over wire 34, front contact 35 of relay R^1 , wire 36, front contact 37 of relay R^2 , wire 38, front contact 30 of relay Q^E , wire 31, front contact 32 of relay L^1 , wires 33 and 25, and winding of relay L^1 to terminal Y. It follows, therefore, that if relay L^1 is once energized, as by the de-energization of relay R^3 , or by operation of push button Z, the relay will subsequently be maintained in its energized condition as long as relay Q^E is de-energized. If relay Q^E becomes energized, however, the locking relay L^1 is held in its energized condition only if track relays R^1 and R^2 of approach section A—C for traffic moving from left to right are both energized.

The relay L^2 is provided with two pick-up circuits similar to the pick-up circuits already traced for relay L^1 and controlled respectively by relay R^3 and push button Z. It follows that the locking relay L^2 is picked up by de-energization of relay R^3 or by the actuation of the push button Z. Relay L^2 having once been energized, is held closed as long as signal relay Q^W is de-energized, by virtue of a stick circuit which passes from terminal X, over wire 39, back contact 40 of relay Q^W , wire 41, front contact 42 of relay L^2 , wires 43 and 44 and winding of relay L^2 to terminal Y. If relay Q^W is energized, however, the stick circuit for relay L^2 is controlled by traffic conditions in

one or the other of the approach sections for traffic moving from right to left, comprising section G—H for the siding and section D—F for the main track, depending upon the position of relay K. For example if relay Q^W is energized and if switch 3 is normal so that relay K is energized in the normal direction, the stick circuit for relay L^2 passes from terminal X, over wire 45, front contact 46 of relay R^6 , wire 47, front contact 48 of relay R^5 , wire 49, normal contact 50 of relay K, wire 99, front contact 51 of relay K, wire 52, front contact 40 of relay Q^W , wire 41, front contact 42 of relay L^2 , wires 43 and 44, and winding of relay L^2 to terminal Y. If, however, switch 3 is reversed, and if relay Q^W is energized, the stick circuit for relay L^2 passes from terminal X, through wire 53, front contact 54 of relay R^4 , wire 55, reverse contact 50 of relay K, wire 99, front contact 51 of relay K, wire 52, front contact 40 of relay Q^W , wire 41, front contact 42 of relay L^2 , wires 43 and 44, and winding of relay L^2 to terminal Y.

The switch 3 is actuated by a motor which in the form here shown comprises an armature 91 and a field 92 and which is in turn controlled by two switch relays, or route stick relays, P^R and P^N . The switch relays P^R and P^N are controlled by the locking relays L^1 and L^2 and also by selectors W^1 and W^2 . As shown in the drawing the switch 3 occupies its normal position and the switch relays P^R and P^N are both de-energized so that the motor M is de-energized, but relays L^1 and L^2 are both energized. If, now, selector W^1 is operated to close contact 12, current flows from terminal X, over wire 56, front contact 57 of relay R^3 , wires 58, 70 and 71, contact 12 of selector W^1 , wires 72 and 73, winding of relay P^R , wires 74 and 75, front contact 76 of relay L^1 , wire 77, and front contact 78 of relay L^2 to terminal Y. Relay P^R therefore becomes energized. After a brief interval of time, contact 12 of selector W^1 opens, but relay P^R is subsequently held in its energized condition by means of a stick circuit which passes from terminal X, over wire 56, front contact 57 of relay R^3 , wires 58 and 59, back contact 79 of relay Q^E , wire 80, back contact 81 of relay Q^W , wire 82, contact 8—8^b of circuit controller J, wire 83, back contact 84 of relay P^N , wire 85, front contact 86 of relay P^R , wires 87 and 73, winding of relay P^R , wires 74 and 75, front contact 76 of relay L^1 , wire 77 and front contact 78 of relay L^2 to terminal Y. It should be noted that the stick circuit for relay P^R includes back contacts on the signal relays Q^E and Q^W so that the switch relay P^R can not be held closed unless the signal relays are both de-energized to insure that the associated signals all indicate stop. Furthermore, both the pick-up and the stick circuits of the switch relay P^R include front contacts of the track relay R^3 and the locking relays L^1 and L^2 .

When relay P^R is energized, current flows from terminal X, over wire 88, front contact 89 of relay P^R , wire 90, armature 91 of motor M, wire 93, back contact 94 of relay P^N , wire 95, contact 9—9^a of circuit controller J, wire 96, and field 92 of motor M to terminal Y. The motor M is therefore energized and operates to drive switch 3 toward its reverse position. When the switch attains its full reverse position, contact 8—8^b opens to break the stick circuit for relay P^R , to de-energize motor M. The motor circuit is also opened at contact 9—9^b, which is open when the switch occupies its reverse position.

The control of relay P^N by selector W^2 is simi-

- far to that already described in connection with the control of relay P^R by selector W^1 , and it will therefore be plain that if selector W^2 is operated, relay P^N will be picked up, and stuck up over contact 8-8^a of circuit controller J. When relay P^N is energized, current from terminal X flows over wires 88 and 88^a front contact 94 of relay P^N , wire 93, armature 91 of motor M, wire 90, back contact 89 of relay P^R , wire 100, contact 9-9^a of circuit controller J, wire 96, and field 92 of motor M, to terminal Y. When this circuit is closed, the motor M is operated to move switch 3 to its normal position. When the switch has attained its full normal position, the opening of contact 9-9^a interrupts the circuit for motor M. It should also be observed that the stick circuit for relay P^N includes contact 8-8^a, so that when the switch is restored to its normal position, the relay P^N becomes de-energized.
- 20 It will be observed that the circuits for the switch relays P^R and P^N each include front contacts on the locking relays L^1 and L^2 . It is therefore impossible to operate the switch 3, except when the locking relays are both energized.
- 25 Under normal conditions, that is, when the signal relays Q^E and Q^W are both de-energized so that all signals indicate stop, the locking relays L^1 and L^2 are stuck up over back contacts of the signal relays. Furthermore, if either of the signal relays is energized to clear the corresponding signal, the relays L will continue in their energized condition provided the track relays are all energized. The circuits are so arranged, however, that if a train enters the approach section 30 for the switch when the signal has been cleared for governing traffic in the direction in which such train is travelling, one of the locking relays L will be de-energized, thereby preventing operation of the switch 3. For example, I will assume that the switch occupies its normal position and that relay Q^E has been energized to clear signal S^1 . Under these conditions, the stick circuit for relay L^1 passes over front contacts of the relays R^1 and R^2 . If, now, a train moving from left to right, approaches the switch 3 and enters either of sections A-B or B-C, the de-energization of the corresponding track relay will interrupt the stick circuit for relay L^1 and will cause this relay to become de-energized. Of course, relay L^2 remains in its energized condition but the opening of front contact 76 of relay L^1 opens both the pick-up and stick circuits for both relays P^R and P^N so that it is impossible to operate the switch 3. It should be noted that if the train continues to move toward the right and enters the switch section C-D, the de-energization of relay R^3 completes a pick-up circuit for relay L^1 . If, now, relays R^1 and R^2 both become energized, the stick circuit for relay L^1 is re-established and the switch may be operated, by picking up one of the switch relays F, as soon as the train has left section C-D to allow relay R^3 to become energized. In similar manner, if switch 3 occupies its normal position, and signal relay Q^W is energized, the relay L^2 is stuck up over front contacts of relays R^5 and R^6 . If a westbound train approaches the switch under these conditions, the relay L^2 will become de-energized as soon as the train passes point F 70 and it will therefore be impossible to operate the switch 3 until relay L^2 has again been energized as by the entrance of the train into section C-D, and relay R^3 has subsequently been re-energized. It should be observed, however, that if relay Q^W is energized with switch 3 reversed to clear signal S^4 , the stick circuit for relay L^2 is controlled by relay R^4 , so that under these conditions the apparatus is locked up by the approach of a westbound train toward the switch along the siding 4, as soon as such train passes point H.
- Under some conditions of operation it is desirable to release the approach locking without requiring the train to actually enter the section which contains the switch. It is for this purpose that the push button Z is provided, and it should be noted that when a train approaches a cleared signal, thereby de-energizing one of the locking relays L^1 or L^2 , the locking relay may again be picked up by the operation of push button Z. If the signal relays Q may have been de-energized in the meantime, the locking relays will remain in the energized condition after operation of push button Z, so that the switch may then be operated from the despatcher's office. It should be observed that signals may be cleared and restored to the stop position without causing de-energization of the locking relays L provided no train accepts the clear signal by approaching when the signal is at clear position. For example, with switch 3 normal, relay Q^E may be energized to clear signal S^1 and the selector W^5 may then be operated to de-energize relay Q^E and restore the signal to stop without affecting relay L^1 , although if relay Q^E is energized, relay L^1 would become de-energized if a train entered section A-B. In order to bridge the interval of time required for operation of relay Q^E , relay L^1 may be made slightly slow acting, or the front and back points of contact 30 of relay Q^E may be made to overlap. In similar manner the parts are so arranged that relay L^2 remains closed during an operation of relay Q^W .
- Although I have herein shown and described only one form of railway traffic controlling apparatus embodying my invention, it is understood that various changes and modifications may be made therein within the scope of the appended claims without departing from the spirit and scope of my invention.
- Having thus described my invention, what I claim is:
1. In combination with a railway switch, a contact, manually controlled means for at times operating said switch provided said contact is closed, a signal governing traffic over said switch, a signal relay controlling said signal, means effective when said signal relay occupies one position to hold said contact closed independently of traffic conditions adjacent the switch, and means effective when the signal relay occupies a different position to hold said contact closed provided the track adjacent said switch is unoccupied.
  2. In combination with a railway switch, a manually controlled signal relay, a signal controlled by said signal relay and governing traffic over said switch, a track relay responsive to traffic conditions adjacent said switch, a locking relay provided with a pick-up circuit, a first stick circuit for said locking relay including a back contact of said signal relay, a second stick circuit for said locking relay including a front contact of said signal relay and a contact of said track relay, and manually controlled means effective when said locking relay is energized to operate said switch.
  3. In combination with a railway switch, a manually controlled signal relay, a signal controlled by said signal relay and governing traffic over said switch, a push button located in the trackway, a track relay responsive to traffic con-

- ditions adjacent said switch, a locking relay, a pick-up circuit for the locking relay controlled by said push button, a first stick circuit for said locking relay including a back contact of said signal 5 relay, a second stick circuit for said locking relay including a front contact of said signal relay and controlled by said track relay, a manually operable selector, a switch relay controlled by said selector and by said locking relay, and a motor controlled by said switch relay for operating said switch.
4. In combination with a railway switch, a manually controlled signal relay, a signal controlled by said signal relay and governing traffic 15 over said switch, a push button located in the trackway, an indication relay controlled in accordance with the position of said switch, a locking relay, a pick-up circuit for the locking relay controlled by said push button, a first stick circuit 20 for said locking relay including a back contact of said signal relay, a second stick circuit for said locking relay including a front contact of said signal relay and a contact of said indication relay and responsive to traffic conditions adjacent the 25 switch, a manually operable selector, a switch relay controlled by said selector and by said locking relay, and a motor controlled by said switch relay for operating said switch.
5. In combination with a stretch of main rail- 30 way track, a siding, a railway switch for at times connecting said siding with said stretch, a manually controlled signal relay, a signal controlled by said signal relay for governing traffic over said switch, a polar indication relay responsive to the 35 position of said switch, a locking relay provided with a pick-up circuit, a first stick circuit for said locking relay including a back contact of said signal relay, a second stick circuit for said locking relay including a front contact of said signal relay 40 and responsive to traffic conditions in said siding or in said main track depending upon the condition of said indication relay, and means controlled by said locking relay for operating said switch.
- 45 6. In combination, a section of railway track, a track relay for said section, a manually controlled signal relay, a locking relay, a pick-up circuit for said locking relay including a back contact of said track relay, manually operable means for 50 energizing said locking relay, a first stick circuit for said locking relay including a back contact of said signal relay, a second stick circuit for said locking relay including a front contact of said signal relay and responsive to traffic conditions 55 adjacent said section, and a railway switch in said section controlled by said locking relay.
7. In combination, a section of railway track, a railway switch in said section, manually controlled mechanism for operating said switch, a 60 railway signal governing traffic through said section, manually controlled means for controlling said signal, a manually operable push button, means set into operation when a train approaches said section while said signal is clear for rendering said mechanism ineffective to operate said switch until said train has passed through said section or until said push button is operated.
8. In combination, a section of railway track containing a railway track switch, a signal for 70 governing traffic movements over said switch, a control circuit for said signal, a track relay for said section, a locking relay, a pick-up circuit for said locking relay controlled by said track relay, a stick circuit for said locking relay controlled by 75 said signal control circuit, a switch relay con-
- trolled by said locking relay and by said track relay, and means controlled by said switch relay for operating said switch.
9. In combination, a section of railway track containing a railway track switch, a signal for governing traffic movements over said switch, a control circuit for said signal, a track relay for said section, a locking relay controlled by said track relay and by said signal control circuit, a third relay controlled by said locking relay and by said track relay, and means controlled by said track relay for controlling said switch. 80
10. In combination with a railway track switch, an indication relay responsive to the condition of said switch, a signal for governing traffic over said switch, a control circuit for said signal, a stick relay, a manually controlled pick-up circuit for said stick relay, a stick circuit for said stick relay controlled by said indication relay and by said signal control circuit, and means controlled by said stick relay for operating said switch. 85
11. In combination with a railway track switch, an indication relay responsive to the condition of said switch, a signal for governing traffic over said switch, a control circuit for said signal, a stick relay, a manually controlled pick-up circuit for said stick relay, a stick circuit for said stick relay controlled by said indication relay and by said signal control circuit, operating mechanism for said switch, and means controlled by said stick 90 relay for at times disabling said mechanism. 100
12. In combination with a railway track switch, an indication relay responsive to the condition of said switch, a signal for governing traffic over said switch, a control circuit for said signal, a stick relay, a manually controlled pick-up circuit for said stick relay, a stick circuit for said stick relay controlled by said indication relay and by said signal control circuit, operating mechanism for said switch, and means operating when said stick relay is deenergized to disable said mechanism. 115
13. In combination, a section of railway track containing a railway track switch, a signal for governing traffic movements over said switch, a control circuit for said signal, a track relay for said section, a locking relay, a pick-up circuit for said locking relay controlled by said track relay, a stick circuit for said locking relay which is energized only if said signal control circuit is energized, a stick relay, a pick-up circuit for said stick relay controlled by said track relay, a stick circuit for said stick relay controlled by said locking relay, and means controlled by said stick relay for controlling said switch. 120
14. In combination, a section of railway track containing a switch, a track circuit for said section including a track relay, a signal for governing traffic movements over said switch, a control relay for said signal, a stick relay, a pick-up circuit for said stick relay controlled by a back contact of said track relay, a stick circuit for said stick relay energized only if said signal control relay is energized, and means effective only when said stick relay is energized for controlling said switch. 125
15. In combination, a railway track switch, an indication relay responsive to the condition of said switch, a signal for governing traffic movements over said switch, a manually controlled circuit for said signal, a stick relay having a pick-up and a stick circuit one of which is controlled by traffic conditions and the other of which is controlled by said indication relay and is energized only if said signal control circuit is 145 150

- energized, and means controlled by said stick relay for operating said switch.
16. In combination, a main section and an approach section of railway track, a switch in said main section, a signal for governing traffic movements over said switch, a control relay for controlling said signal, a stick relay, a pick-up circuit for said stick relay controlled by traffic conditions in said main section, a stick circuit for said stick relay controlled by traffic conditions in said approach section when said control relay is energized and controlled independently of traffic conditions when said control relay is deenergized, and means controlled by said stick relay for operating said switch. 80
17. In combination, a main and an approach section of railway track, a switch in said main section, a signal for governing traffic movements over said switch, a control circuit for said signal, two track relays one for each said section, a manually operable circuit controller, a stick relay having pick-up and stick circuits one of which is controlled by one of said track relays and is energized if and only if said signal is controlled to display a proceed indication and the others of which are controlled by said circuit controller and by the other of said track relays, and means controlled by said stick relay for operating said switch. 85
18. In combination, a section of railway track including a switch, a track circuit for said section including a track relay, a signal for governing traffic movements over said switch, a signal control relay, a circuit for clearing said signal including front contacts of the signal control relay and of the track relay, an approach track section adjacent said switch track section, and means for operating said switch effective when said signal control relay is energized only if said approach section is clear. 90
19. In combination, a railway track switch, an indication relay responsive to the condition of said switch, a signal for governing traffic movements over said switch, a control circuit for said signal, an approach track section, a second approach track section, a stick relay, a manually controlled pick-up circuit for said stick relay, a stick circuit for said stick relay controlled by said signal control circuit and also controlled by traffic conditions in said first approach section if and only if said indication relay responds to a given condition of said switch, a second stick circuit for said stick relay controlled by said signal control circuit and also controlled by traffic conditions in said second approach section if and only if said indication relay responds to a second condition of said switch, and means controlled by said stick relay for operating said switch. 95
20. In combination, a railway track switch, an indication relay responsive to the condition of said switch, an approach track section, a second approach track section, a stick relay, a manually controlled pick-up circuit for said stick relay, a stick circuit for said stick relay controlled by traffic conditions in said first approach section if and only if said indication relay responds to a given condition of said switch, a second stick circuit for said stick relay controlled by traffic conditions in said second approach section if and only if said indication relay responds to a second condition of said switch, and means controlled by said stick relay for operating said switch. 100
21. A railway system having a track switch and a plurality of signals for governing traffic movements over said switch, a pair of relays at said switch for controlling said switch, manually operable control means at a remote point for transmitting code signals to selectively operate one or the other of said relays to control said switch, and means for preventing the operation of either of said relays if a train approaches within a given distance of one of said signals while the signal is displaying a proceed indication. 105
22. In combination, a railway track switch having a normal and a reverse position, a signal for governing traffic movements over said switch, a first and a second switch relay, a circuit for energizing said first switch relay for causing an operation of said switch to its normal position, a second circuit for energizing said second switch relay for causing an operation of said switch to its reverse position, an approach locking relay which becomes deenergized if a train approaches said switch while said signal is controlled to display any other than a stop indication, and means controlled by said approach locking relay for deenergizing said switch relays if said approach locking relay is deenergized. 110
23. A system of railway traffic route signaling comprising a switch and a plurality of signals for governing traffic movements over said switch, a pair of route stick relays, a pair of traffic direction stick relays, means for energizing one or the other of said route stick relays for causing an operation of said switch to its normal or its reverse position respectively, means for energizing one or the other of said traffic direction stick relays for clearing a signal for a given direction of traffic movement or for the opposite direction respectively, approach locking means for preventing energization of said route stick relays but permitting energization of said traffic direction stick relays, and means for rendering said approach locking means effective to deenergize said route stick relays when a train approaching one of said signals arrives at a given point if and only if the signal is controlled to display a proceed indication. 115
24. In combination, a section of railway track containing a track switch over which traffic may move in either of two directions, selecting means manually controllable from a point remote from the switch for operating the switch and for governing the direction of traffic movement over the switch, an approach locking relay, means for deenergizing said relay when a given direction of traffic is established by said selecting means provided a train approaching in said direction is within a predetermined distance of the switch, but for maintaining said relay energized at other times independently of traffic conditions, and means effective when said relay is deenergized for preventing operation of said switch by said selecting means. 120
25. In combination, a section of railway track containing a track switch over which traffic may move in either of two directions, manually controllable selecting means for governing the direction of traffic movement over the switch, an approach section adjacent said switch section, an approach locking relay, means for controlling said relay in accordance with the condition of said approach section when and only when said selecting means is controlled to permit a traffic movement in the direction from said approach section to said switch section, and means con- 125

trolled by said approach locking relay for controlling said switch.

26. In combination, a section of railway track containing a track switch over which traffic may move in either of two directions, manually controllable selecting means for operating said switch and for governing the direction of traffic movements over the switch, two approach locking relays one for each direction; means for deenergizing one of said relays when one direction of traffic is established, and for deenergizing the other relay when the other direction of traffic is established by said selecting means provided a train moving in the direction established is within a predetermined distance of said switch; and means effective when either of said relays is deenergized for preventing operation of said switch by said selecting means.

27. In combination, a stretch of railway track over which traffic may move in either direction comprising a section containing a track switch and two approach sections one at each end of said switch section, manually controllable selecting means for governing the direction of traffic movement over the switch, an approach locking relay for each approach section, means for controlling each said relay in accordance with the condition of the corresponding approach section when and only when the selecting means is controlled to permit a traffic movement in the direction from such section to the switch section, and means controlled by said approach locking relays for controlling said switch.

28. In combination, a stretch of railway track over which traffic may move in either direction comprising a section containing a track switch and two approach sections, including one at each end of said switch section, manually controllable selecting means for governing the direction of traffic movement over the switch, an approach locking relay for each approach section, means for deenergizing each said relay when the corresponding approach section is occupied and the selecting means is controlled to permit a traffic movement in the direction from such section to the switch section, means for energizing each said relay when the switch section becomes occupied, and means for operating the switch effective only when the switch section is unoccupied and both said relays are energized.

29. In combination, a section of railway track containing a track switch, a pair of opposing signals for governing traffic over the switch, a track circuit for said switch section having a track relay, manually controllable selecting means effective when said track relay is energized to clear one signal or the other to permit the movement of traffic over the switch in one direction or the other, two approach locking relays one for each direction, a pickup circuit for each approach locking relay including a back contact of said track relay, a stick circuit for each approach locking

relay arranged to be opened when said selecting means is operated to permit the movement of traffic over the switch in the corresponding direction, but not when said means is operated to permit the movement of traffic over the switch in the reverse direction, and means controlled by both said approach locking relays and by said track relay for controlling said switch.

30. In combination, a stretch of railway track comprising a section containing a track switch and two approach sections one at each end of said switch section, two signals one at each end of said switch section for governing traffic approaching said switch through the adjacent approach section, a stick relay for each signal, manually controllable signal selecting means for selectively energizing one stick relay or the other, or for releasing such relay when energized, manually controllable switch control means for operating the switch effective only when both said stick relays are deenergized, and approach locking means arranged to prevent operation of the switch control means provided one of said stick relays becomes deenergized when the approach section adjacent the signal controlled by such relay is occupied by a train.

31. In combination, a railway track switch having a normal and a reverse position, a polar indication relay energized in one direction only when the switch is normal and in the other direction only when the switch is reversed, a signal for governing the movement of traffic over said switch, a signal control relay for said signal, an approach track section, a second approach track section, a stick relay, means for picking up said stick relay, a first stick circuit for said stick relay controlled by said signal control relay and by traffic conditions in said first approach section if and only if said indication relay is energized in said one direction, a second stick circuit for said stick relay controlled by said signal control relay and by traffic conditions in said second approach section if and only if said indication relay is energized in said other direction, and means controlled by said stick relay for operating said switch.

32. In combination with a switch section of railway track containing a track switch adapted to be operated to one position for traffic approaching said switch from an adjacent main track section and to another position for traffic approaching said switch from an adjacent siding, an approach locking stick relay, a pickup circuit for said relay closed only when said switch section is occupied, stick circuits for said relay controlled by a train approaching said switch in said main track section or in said siding in accordance with the position of said switch, and means for preventing the operation of said switch except when said stick relay is energized and said switch section is unoccupied.

PAUL P. STOKER.
